DEAD CENTER DEVICE

Original Filed May 15. 1926

John D. Powers INVENTOR
BY *Elwin S. Clarkson* ATTORNEY.

UNITED STATES PATENT OFFICE

JOHN H. TOWERS, OF BALSAM LAKE, WISCONSIN

DEAD-CENTER DEVICE

Original application filed May 15, 1926, Serial No. 109,401. Divided and this application filed June 6, 1927. Serial No. 196,729.

This is a division of my application filed May 15, 1926, Serial No. 109,401.

This invention relates to an improved mechanical movement designed to be employed for converting reciprocating movement into movement of rotation, the object of the invention being to provide an assemblage of mechanical elements which will co-operate to overcome dead centers.

10 The invention is applicable for use in connection with steam engines, gas engines, windmills, hand operated devices, or in any relation wherein it is desired to overcome dead centers.

15 Illustrative embodiments of the invention are shown in the accompanying drawings in which:

Figure 1 is a side view of the device shown connected at one end to a reciprocating piston and at the other to a wheel.

Figure 2 is an end view of the same.

20 Figure 3 is a modification of the device. In the drawings the reference numeral 1 denotes a suitable fixed base or support, the 25 numeral 2 denotes a wheel rotating about a fixed center 4 and the numeral 15 denotes a fixed cylinder having a reciprocating piston 14 pivoted with a piston rod 13.

It is desired to transform the reciprocatory 30 movement of the piston rod 13 into rotary movement of the wheel 2 by suitable assemblage of mechanical elements which are so related that they effectively overcome dead center.

35 Pivotedly connected to the piston rod 13 as at 11 is a connecting rod 12, which at its opposite end is pivoted, as at 10, to the vertical arm 8 of an angle crank 5, the horizontal arm of which is connected to a fly wheel 2

40 by means of a crank pin 3. The angle crank is pivoted at 6 to an oscillating rocker arm 7, which is pivoted as at 9 to the stationary support 1, as shown. The pressure cylinder 21 is provided with a piston 20 having a 45 piston rod 19 which is connected at 18 to the connecting rod 16. This connecting rod 16 is connected at 6 to the rocker arm 7.

Suitable valves are connected to the cylinder 21 as at 22 and 23 which control the 50 pressure supply, and permit compressed fluid

to enter at will to chamber 24, or 25, of said cylinder 21, depending on the direction of rotation of the wheel 2.

The rocker arm 7 is adapted to swing to and fro as a pendulum, oscillating about a fixed pivot and carries with it the oscillating pivot 6 which swings in the arc of a circle indicated by the arrows.

Assuming now that the mechanism is in a position shown in the full lines in Figure 1, and that compressed fluid enters into pressure cylinder 21 in the chamber 25 and remains a constant pressure as long as the wheel is to rotate in this direction.

Compressed fluid is allowed to enter into cylinder 15 in chamber 27, whereupon the piston 14 is moved to the right in the direction of the arrow. When the angle crank has reached the position indicated in the full lines or what would be a dead center position, the pressure still acting on piston 14 throws the pivot 3 past the dead center, at this moment, due to the downward pressure on piston 20 and gives the wheel 2 continuous motion, the same thing happens at the opposite dead center, and the wheel continues to rotate in a counter clockwise direction.

Obviously, if the force operating from the piston 20, upon the pivot 6 or any other point on the rocker arm whether extended or not past pivot 6, were reversed as for instance; if the valve 23 is opened to allow pressure to enter chamber 24 of cylinder 21 (the pressure, of course, is allowed to exhaust from chamber 25) in cylinder 21 the direction of rotation of the wheel 2 will be reversed but the action of overcoming dead centers is the same.

Many changes may be restorted to without departing from the spirit of the invention.

For example, the angle crank could be a T crank and the power applied below the pivot 6 and a reverse motion will be the result from the direction as shown in Figure 1 of this drawing. Likewise, in place of the compression cylinder, any means may be employed which will produce a pressure upon the oscillating pivot on rocker arm 7, which pressure acts in cooperation with arm of the

crank which is attached to the wheel or rotary element.

What I claim is:

1. A device for overcoming dead centers comprising a rocker arm oscillating about a fixed pivot, an angle crank pivotally connected to the oscillating end of the rocker arm, one arm of said crank being connected to a rotary element, and the other adapted to be operated from a suitable source of power, and means acting to produce pressure upon the oscillating pivot of said crank, and means for reversing at will the direction of force of said means.
2. A device for overcoming dead centers, comprising a rocker arm, an angle crank pivotally mounted on the oscillating end of said rocker arm, a connecting rod pivotally connected at one end with the oscillating end of said rocker arm, a piston pivotally connected to the other end of said connecting rod, and a rotary element connected with the other end of the angle crank.
3. A device for overcoming dead centers, a rocker arm pivotally mounted at one end to a suitable support, an angle crank pivotally mounted on the oscillating end of said rocker arm, one end of the angle crank being connected to a rotary element, while the other end is connected with a suitable source of power, a connecting rod pivotally connected at one end to the oscillating end of the rocker arm, a cylinder, a piston in said cylinder, a pressure port at each end of the cylinder, said piston being pivotally connected to the other end of said connecting rod.

In testimony whereof I affix my signature,
JOHN H. TOWERS.
